UNITED STATES PATENT OFFICE.

FERDINAND W. KROGH, OF SAN FRANCISCO, CALIFORNIA.

PUMP FOR DEEP WELLS.

No. 927,057.

Specification of Letters Patent.

Patented July 6, 1909.

Application filed February 26, 1906. Serial No. 303,040.

To all whom it may concern:

Be it known that I, FERDINAND W. KROGH, a citizen of the United States, residing in the city and county of San Francisco, State of California, have invented certain new and useful Improvements in Pumps for Deep Wells, of which the following is a specification.

My invention relates to deep well pumps, and more especially to the valves of the pump, and mechanism for rendering the same accessible.

In carrying out my invention I proceed as follows:—Take the case of a double acting pump, for example—I provide a sleeve which fits within the well casing, and may be lowered in the same to the desired point near the bottom. This sleeve carries both discharge valves and one of the suction valves ordinarily. The suction valve and one of the discharge valves I seat upon the well casing, through an opening in the sleeve, and this opening is caused to register with the seat by means of a guide, such as a slot and pin, which acts upon the sleeve as it is lowered into place. To keep the sleeve in position, when down, I provide it with one or more dogs to bite into the well casing. When the sleeve is to be raised the piston is drawn up and engages these dogs and releases them from their hold on the casing, and the sleeve is then drawn out with the piston, and carries the valves with it. The second suction valve, which is lower down in the well casing, may be similarly arranged in a sleeve, or in place of the sleeve I may use its equivalent, a central stem to support and connect the parts. I also use a bypass in connection with the above, by which the water is carried from below the piston on the downward stroke of the same.

The invention consists in the various devices and combinations of the above construction, and in such other instrumentalities as may be described hereinafter and more particularly defined in the claims at the end hereof.

In the accompanying drawings I have shown my invention in its best form as applied to a double acting deep well pump.

Figure 1 is a sectional longitudinal view, showing part of a well with the casing and the sleeve therein carrying the upper valves, and showing in elevation the piston below

the sleeve. Fig. 2 is a similar view showing the lower end of the well casing with the lower valves, and the piston above them, and the devices for lifting them out by means of the piston. Fig. 3 shows the piston engaging the central stem of the lower valves, and the dogs of the sleeve, carrying the upper valves, and raising those parts with it as it is drawn up. Fig. 4 is a cross section on line 4, 4 of Fig. 2, and shows the hooks on the under side of the piston for raising the lower valves.

1 represents the well, and 2 the casing.

3 is the bypass of the casing.

4 is the piston, and 5 the piston rod.

6 is a sleeve, fitting within the well casing 70 2, and adapted to rest by a flange or shoulder 7 upon a shoulder 8 of the casing.

9 is the discharge valve for the lower end of the pump cylinder. This valve is carried by the sleeve, as shown, but is seated upon the casing over the discharge orifice 10, which it is adapted to close. The casing is provided with a groove 11, which engages a pin 12 on the sleeve, and thus insures the sleeve coming to place so that the valve 9 80 will register with its seat. The sleeve, of course, has an opening in its side in which the valve swings.

13 are the discharge valves for the upper end of the pump cylinder. These valves are 85 also carried by the sleeve, and are arranged centrally on inclined seats 14, as shown, so that the water passing through them has a direct upward course to the final outlet.

15 is a central tube or sleeve about the piston rod 5, and carries a stuffing box 16 to prevent leakage about the rod.

17 is the suction valve for the upper end of the pump cylinder. It is supported on the sleeve 6 similarly to the valve 9, and like 95 that valve, seats upon the casing over the suction opening 18, and its register therewith is insured by the same means as that of the valve 9, namely, the pin and groove, 11, 12. Near the bottom of the sleeve, or at 100 other convenient point, I arrange dogs 19, which normally engage the well casing 2 by their pointed ends as shown. These dogs are disengaged from the casing, when it is desired to draw up the sleeve, by the piston 4, 105 which, being drawn up comes against the tails 20 of the dogs and turns them on their pivots 21, as shown in Fig. 3.

22 are the suction valves for the lower end of the pump cylinder. These valves are arranged on inclined seats 23 on a central spider or skeleton consisting of a ring 24, a 5 ring 25, and a central stem 26 connecting those rings and joined to them by arms 27.

28 are springs to close the valves.

The spider rests upon a flange of the casing at 29, and is maintained in that position by 10 the dogs 30, which bite the casing 2.

31 are arms depending from the bottom of the pump piston, and 32 are hooks on the lower ends of these arms.

When it is desired to draw out the central 15 spider from the casing, the piston is lowered till the hooks 32 pass below the dogs 30, it is then turned to bring the hooks under the dogs, and then raised, when the hooks coming against the tails 33 of the dogs, turns 20 them on their pivots 34, to the position shown in Fig. 3, with their points free from the casing, when the whole mechanism may be withdrawn. To prevent injury to the dogs by the turning of the piston, I provide a 25 head 35 upon the upper end of the stem 26, against which the arms 31 contact when the piston is turned to cause the hooks 32 to pass under the dogs.

I claim:—

30 1. In a deep well pump, the combination with the casing and the piston and its rod of valves arranged on opposite sides of the piston, separate supports for said valves each provided with means for locking it in position, and devices movable with the piston for releasing the locking means and withdrawing the supports, one of said devices arranged below the piston.

2. In a deep well pump, the combination 40 with the casing and the piston and its rod of valves arranged on opposite sides of the piston, separate supports for said valves each provided with means for locking it in position, and devices movable with the piston for 45 releasing the locking means and withdrawing the supports, one of said devices arranged below the piston and normally free from engagement with the lower valve-support.

3. In a deep well pump, a piston and a 50 ton casing having a lateral opening, combined with a sleeve slidably mounted in the piston casing and provided with an opening registered with the lateral opening thereof and with a valve seat and with means for 55 locking it removably in place in the casing, said sleeve also provided with a valve for controlling communication through the registered openings in the casing and sleeve and with a second valve on said valve seat, and 60 means moving with the piston and arranged to release the locking means and to remove the sleeve and valves with the piston.

4. In a deep well pump, a piston casing 65 having a lateral opening and a piston, combined with a sleeve slidably mounted in the

casing and having its side wall provided with an opening which is registered with the lateral opening of the casing and with a valve which controls communication through these openings, said sleeve also provided with a 70 valve seat arranged inclinatorily and with a second valve upon said seat, means for locking the sleeve removably in place in the casing and means moving with the piston and arranged to release the locking means and to 75 remove the sleeve and valves with the piston.

5. In a deep well pump, in combination with the casing, a valve carrying sleeve adapted to be lowered into the casing to bring the valves into operative position, and valves 80 mounted on said sleeve, and seats for such valves arranged upon the casing.

6. In a deep well pump, a casing and a valve support, having lateral registered openings, a valve carried by the support and 85 seated on the casing and controlling communication of the same with each other through said openings.

7. In a deep well pump, a casing and a valve support, having lateral registered openings, a valve carried by the support and 90 seated on the casing and controlling communication of the same with each other through said openings, said support slidably mounted in the casing, means for locking the support 95 in its normal position, therein, and means for releasing the lock and raising the support from the casing.

8. In a deep well pump, a casing having a plurality of lateral openings, a valve support 100 slidably mounted in the casing and having a plurality of lateral openings registered with those of the casing, and provided with valvular means controlling said registered openings and with other valvular means between its 105 lateral openings, valvular means slidably supported in the casing and arranged below the lateral openings, a piston and means connected with the piston, for raising the valves and their supports from the casing.

9. In a deep well pump, a casing having discharge and suction openings, a sleeve slidably mounted in said casing and provided with lateral openings registered with the discharge and suction openings thereof and with 115 valves which control said openings, said sleeve also provided with discharge valves arranged between said openings, suction valves below said openings, locking means for holding the parts in proper position in 120 the casing, a piston and means connected with the piston and adapted to release the locking means and raise the sleeve and valves from the casing.

10. In a deep well pump, a casing having 125 discharge and suction openings, a sleeve slidably mounted in said casing and provided with lateral openings which are registered with said discharge and suction openings respectively, said sleeve also provided with 130

valves which control said openings and with a discharge valve arranged between said openings, means for holding the sleeve in the casing and means adapted to raise the sleeve 5 and said valves with the piston.

11. In a deep well pump, a piston having depending projections provided with hooks, a valve and its support arranged below the piston and having locking means adapted to 10 be released by the hooks, said hooks and locking means being normally free from engagement with each other and relatively movable to effect such engagement.

12. In a deep well pump, a casing, a piston 15 ton, a valve and its support arranged below the piston and having dogs to engage the casing, and projections depending from the piston and adapted to release said dogs and connect the piston and valve support for 20 unitary removal from or insertion into the casing.

13. In a deep well pump, a casing, a piston, a valve and its support arranged below the piston, said support having a head and 25 dogs arranged below the head and adapted to lock the support to the casing, said piston normally movable relatively to the support and provided with depending hooked projections adapted to engage the dogs and release the same from the casing and connect 30 the piston and support with each other for unitary removal from or insertion into the casing.

14. In a deep well pump, a casing having 35 discharge and suction openings, a piston and its rod, a sleeve slidably mounted in the casing and provided above the piston with lateral openings which are registered with said discharge and suction openings respectively 40 and with valves which control said openings, said sleeve also having valve seats between said openings and discharge valves on said seats, means for holding the sleeve in the

casing and means adapted to raise the sleeve and said valves with the piston. 45

15. In a deep well pump, a casing having a by-pass provided with a lateral discharge opening, said casing also having a suction opening, a sleeve slidably mounted in the casing and provided with openings and valves, said valves adapted to close the discharge and suction openings of the casing, said sleeve also provided with a discharge valve arranged between its before-mentioned valves, a suction valve supported below the by-pass, a piston mounted to reciprocate between the sleeve and the last-mentioned valve may be removed from the casing with the piston. 50 55 60

16. In a deep well pump, a casing having a by-pass provided with a lateral discharge opening, said casing also having a suction opening, a sleeve slidably mounted in the casing and provided with openings registered 65 with the openings in the casing and with valves adapted to close the discharge and suction openings of the casing, said sleeve also provided with a discharge valve arranged between its before-mentioned valves 70 and with means for locking it in position, a suction valve supported below the by-pass, means for locking it in position, a piston mounted to reciprocate between the sleeve and the last-mentioned suction valve, and 75 means movable with the piston and adapted to engage the locking means of the sleeve and support of the suction valve for removing the same with the piston.

In testimony whereof I have hereto set my 80 hand in presence of two subscribing witnesses this 8th of December, 1905.

FERDINAND W. KROGH.
